Specification of Letters Patent. Patented May 26, 1914.

Original application filed August 13, 1912, Serial No. 714,857. Divided and this application filed November 9, 1912. Serial No. 730,373.

To all whom it may concern:

Be it known that I, HARRY P. MACDONALD, a citizen of the United States, residing at Montclair, in the county of Essex and State of New Jersey, have invented certain new and useful Improvements in Treads, of which the following is a specification.

This invention relates to treads for stairs, sidewalks and similar forms of pavement and is a division of my co-pending application, Serial No. 714,857, filed August 13, 1912. It has for its primary objects: the provision of an improved safety or non-slipping tread member; the provision of a tread of the character specified which can be conveniently and inexpensively manufactured, and the wearing qualities of which are such as to greatly prolong the life of the tread; the provision of an improved abrasive tread which will not warp or become otherwise distorted in the process of manufacture; and the provision of an improved construction of abrasive non-slipping tread which will retain its non-slipping characteristics until the body of the tread is worn through. These, together with such other objects as may hereinafter appear or are incident to my invention I attain by means of a construction illustrated in preferred form in the accompanying drawings, wherein:

Figure 1 is a plan view of a portion of a metallic stair tread embodying my invention; and Fig. 2 is a section through the tread taken on the line II—II of Figure 1.

The method I preferably employ in manufacturing my improved tread is set forth in the application above referred to, but in order to afford a clear understanding of the invention, a brief statement thereof will be here given. In manufacturing, I propose to cast the body or matrix of the tread and embed therein lumps of abrasive material of a uniform graded size, the abrasive material having a relatively greater degree of hardness than the matrix and the individual lumps being preferably slightly greater in their least dimension than the thickness of the matrix, though the purposes of the present invention may be served by providing lumps of abrasive of approximately the same thickness as the matrix. I preferably employ cast iron for the matrix and alundum, carborundum and like materials for the abrasive or non-slipping elements, such ma-

terial being considerably harder than iron and capable of withstanding a high degree of heat.

As shown in the drawings, the tread comprises a body portion or matrix 7 of cast iron provided with a curved front edge or nosing 8 and having its upper surface interrupted both longitudinally and laterally by checkers 9 of pyramidal shape. Throughout the matrix are lumps 10 of alundum or other abrasive having similar characteristics, the lumps being preferably of cubical or spherical shape with their least dimension slightly greater than the thickness of the matrix. The lumps are preferably so positioned that their bottom portions are practically flush with the lower surface 11 of the matrix and their top portions 12 project through the apexes of the checkers, slightly above the top surface 13 of the matrix. Similar lumps are placed in the nosing in substantially the same relation to the matrix.

This form of construction gives great durability to the tread and increases its life, inasmuch as the metal wears down more rapidly than the abrasive material and a non-slipping surface is assured as long as there is sufficient metal in the matrix to retain the abrasive in position. It will be apparent that the tread will last until the metal of the matrix is worn through.

A further advantage of having the lumps of approximately the same thickness as that of the matrix is that the metal when cast will cool uniformly and warping or other distortion thus prevented. When the abrasive is only embedded adjacent one surface of the tread, the metal will cool unevenly. Another advantageous feature of the construction is that the number of abrasive particles necessary is reduced, with the result that the tread may easily be kept in clean condition. The construction also simplifies the manufacture of the tread, as it will be readily apparent that the lumps can be conveniently maintained in proper fixed position during the casting operation and will not be washed to one side with the flowing metal. It will also be seen that by virtue of the simplicity afforded in manufacture, uniformity of construction throughout the tread is obtained, this being of advantage as it tends to prevent inequality in

wearing properties and thereby insures an extended life to the tread as a whole. Other advantages will occur to those familiar with the art.

5 Another advantage of the construction resides in the fact that, should the tread wear unevenly for some reason or other, or become rough or jagged, it may be reversed, in which event the lower surface will in a 10 very short time become as effective an abrasion non-slipping surface as the upper surface. It will be apparent that this will result in prolonging the life of the tread.

Another advantage incident to the construction is that in manufacturing, uniformity of product is secured by reason of the fact that the abrasive elements will always be in proper relation to the upper surface of the matrix, in view of the fact that the 20 individual lumps are greater in their least dimension than the thickness of the matrix, so that a portion will always project slightly above said surface. This also simplifies manufacture.

25 Having thus described my invention and illustrated its use, what I claim as new and desire to secure by Letters Patent is the following:

1. As an article of manufacture, a tread member comprising a substantially flat cast

metal plate having embedded therein a plurality of lumps of abrasive each of approximately the same thickness as the body of the tread and lying at least flush with one face of the tread and presenting substantially 25 the same aggregate surface of abrasive on each side of the tread so that the tension produced by the casting on the two surfaces of the plate shall be substantially equal so as to avoid warping. 40

2. As an article of manufacture, a tread member comprising a substantially flat cast metal plate having embedded therein a plurality of lumps of abrasive spaced substantially equi-distant from one another and 45 each of approximately the same thickness as the body of the tread, the said lumps lying at least flush with one face of the tread and presenting substantially the same aggregate surface of abrasive on each side of the plate 50 so that the tension produced by the casting on the two surfaces of the plate shall be so nearly equal as to avoid warping.

In testimony whereof I have hereunto signed my name in the presence of the two 55 subscribed witnesses.

HARRY P. MACDONALD.
